UNITED STATES PATENT OFFICE.

AUGUSTUS E. MUTH, OF CINCINNATI, OHIO.

IMPROVEMENT IN DOUGH-MIXERS.

Specification forming part of Letters Patent No. 125,072, dated March 26, 1872.

I, AUGUSTUS E. MUTH, of Cincinnati, Hamilton county, Ohio, have invented a new and useful Cake-Dough Beating and Mixing Machine, of which the following is a specification:

The object of this invention is to furnish to bakers, confectioners, and pastry-cooks a machine, whereby the various manipulations of cake-dough, batter-icing, &c., are enabled to be performed more easily, quickly, and better, and in a far more cleanly manner than such operations are now performed by hand.

My invention is an improvement in the class of mixing-machines in which the dough or mass is confined in a vertical tub or vessel containing a stirrer, which is caused to rotate horizontally in one direction, while the tub is rotated in the opposite direction; and my invention consists in devices whereby the stirring of a single large mass or batch, or of several smaller masses, is more effectually and easily secured than heretofore.

In the accompanying drawing, Figure 1 is an elevation of a machine embodying my improvements, the same being adapted for operating a single large tub. Fig. 2 is a vertical section of my machine adapted for operating with two smaller tubs. Fig. 3 is an enlarged view of my shaft-coupling. Fig. 4 is an axial section of the lower portion of the tub. Fig. 5 shows my stirrer for large masses detached. Fig. 6 is an elevation of my apparatus in its simplest form. Figs. 7 and 8 show modifications of my coupling.

A is a frame, having journaled vertically in its lower portion one or more shafts, B B' B'', and in its upper portion an equal number of shafts, C C' C'', in line with those below, but not connected with them. These shafts B B' B'' and C C' C'' are caused to revolve in opposite directions by means of suitable gearing D, driven either by pulley E, having suitable belted connection with a steam-engine or other motor, or by a winch, F, operated by hand. Near the top of each shaft B B' B'' is a feather, b, which, entering a corresponding groove in the hub G, obliges the said hub and its attached platform H to revolve with the shaft. Pins I, traversing lugs j upon the bottom of the tub J and the platform H, secure the former to the latter, and oblige it to rotate therewith. My preferred form of stirrer for large masses is shown in part in Figs. 1, 2, and 3, and entire

in Fig. 5, and consists, essentially, of a series of rods, K, secured in the horizontal position, severally, one below and at a slight obliquity to that above it, by being passed through and fastened to a bow or head, L, whose shaft M is coupled to the upper shaft C' by means of a feathered coupling or collar, N, and set-screw O; or, instead of the set-screw O, a pin, O' may be used, as in Figs. 7 and 8, the groove e being sunk deeper for a portion of its length so as to limit the descent of the said pin, and, consequently, of the coupling N. The stirrer terminates below in a blade or scraper, P, whose pivot Q is in a line with the shafts B and C, and occupies a step or socket, R, attached to the floor of the tub. The two portions of the scraper P on the respective sides of the pivot are turned oppositely downward so as to scrape up and detach from the tub-floor hard and unblended masses adhering thereto. Attached, by arm S, screw-threaded stem T, and nuts t, to the stirrer-shaft, is a scraper, V, which, projecting perpendicularly from the said stem, operates to perform the same service for the walls of the tub that the scraper P does for its floor.

The nuts t enable the secure attachment of the scraper V in the required position, or of its adjustment toward or from the center, or of its temporary removal or replacement by another scraper.

The spiral and, at the same time, open arrangement of the stirring-rods enables them to pass readily through and yet to thoroughly agitate the mass, and, in conjunction with the scrapers P and V, operates to move every part of the mass at each revolution, the spiral arrangement of the rods also acting to constantly elevate to the top of the mass the thicker and more refractory portions until thorough homogeneity is attained.

For deeper tubs the stirrer K may have a greater height and have a greater number of rods, and for shallower tubs may have fewer rods.

Fig. 2 shows my machine with two smaller tubs, J' J'', and agitators W X in place of the large one shown in Fig. 1.

Fig. 6 shows my apparatus adapted for the lighter use of small establishments and for domestic purposes, and comprises a single stem or shaft and accompanying stirrer.

The supports near the outer ends of rods K

may be omitted and the latter secured in the represented spiral position by passing through suitable apertures in the shaft. In this case the shaft should be extended down to the bottom of the tub, and the lower end of said shaft should be journaled in the step or bearing R.

Claims.

I claim as my invention—

1. The reversely-rotated and interchangeable tubs J J' J'' and stirrers attached, as represented, to lower and upper shafts, having concentric but opposite rotations by connection with driving mechanism, as and for the purpose explained.
2. The series of reversely-rotated tubs and stirrers, convertible to use with a single large tub and stirrer, the whole being arranged and operating as set forth.

3. The described combination with suitable driving mechanism D of the reversely-rotated detachable tubs J and stirrers K, as and for the purpose stated.

4. The combined stirrer and scraper, composed of the rods K, head L, shaft M, blades or scrapers P and V, and pivot Q.

5. In the described combination with the elements of the preceding clause, I claim the arm S, screw-threaded stem T, and nuts U for attachment and adjustment of the side scraper V, as set forth.

In testimony of which invention I hereunto set my hand.

AUGUSTUS E. MUTH.
